UNITED STATES PATENT OFFICE.

JOHN CHARLES SIMMONDS AND ALONZO PENISTON, OF JERSEY CITY,
NEW JERSEY.

SHELL FOR DISTRIBUTING OIL ON WATER.

SPECIFICATION forming part of Letters Patent No. 495,569, dated April 18, 1893.

Application filed January 28, 1892. Serial No. 419,532. (No model.)

To all whom it may concern:

Be it known that we, JOHN CHARLES SIMMONDS and ALONZO PENISTON, of Jersey City, New Jersey, have invented a new and useful 5 Automatic Shell or Receptacle for Distributing Oil on the Waters of a Heavy Sea, of which the following is a specification.

Our invention relates to improvements in an automatic shell or receptacle for conveying 10 oil.

The object of our invention is to construct a shell or receptacle which may be used on board vessels or at life-saving stations; the shell or receptacle to be filled with oil or other 15 substance, and discharged from an air gun or cannon on the waters of a heavy sea for the purpose of calming, tranquilizing and allaying the same. We attain these objects by the mechanism illustrated in the accompanying 20 drawings in which—

Figure 1 is a perspective view showing the same in operation. Fig. 2 is a side view of shell or receptacle in a cartridge to be used in a machine or breech loading gun. Fig. 3 25 is an enlarged sectional view of the shell or receptacle. Fig. 4 is a sectional view showing a shell or receptacle partly open. Fig. 5 is a side view of a shell or receptacle with a feather attached. Fig. 6 is an end view of 30 the feather and one of the cylinder heads. Fig. 7 is a side view of a shell or receptacle discharging as it comes in contact with the water.

Like letters of reference refer to like parts 35 throughout the several views.

In the drawings, Fig. 3, the shell or receptacle, A, is constructed with a glass cylinder, a, which is enveloped in a paper or pasteboard cover, b. At one end of the glass cylinder, a, is a metal head, c, preferably of lead: between the metal head, c, and the glass cylinder, a, is a rubber band or girdle, f. At the other end of said glass cylinder, a, is another metal head, d, which has a shoulder 45 which projects above the opening in the glass cylinder, a: between the inner portion of the head, d, and the glass cylinder, a, is a rubber belt or girdle, g. The body of the glass cylinder a, is filled with oil, and the two heads, 50 c and d, are connected by means of a rod or shaft, e. The metal head, d, is further provided with a feather, h, to give the shell or receptacle a rotary motion when fired from a

smooth bore gun as shown in Fig. 5. It will be observed that the head, c, Fig. 3, in the forward end of the said shell or receptacle is much heavier than the head, d; the object of this being to give it a downward tendency and to strike the water in such a manner as to cause it to open as shown in Fig. 7. 55

We do not limit ourselves to the size of the shell or receptacle or materials mentioned in the specification, as the inner cylinder, a, Fig. 3, may be made of celluloid or other smooth substance, and the outer cylinder or 65 covering, b, may be made of cloth, felt or other substance. The heads, c and d, may be also made of metal or other compound.

Having described our invention, what we claim as new, and desire to secure by Letters 70 Patent, is—

1. The herein-described shell or receptacle having open ends closed by connected movable sections, adapted to be unseated by the weight of the water as the shell strikes its 75 surface, substantially as described.

2. The herein-described shell or receptacle having open ends, connected movable sections for closing said ends, and a steering device for guiding said shell, substantially as 80 described.

3. The herein-described shell or receptacle, having open ends and adapted to be sealed by removable connected sections, one of said sections being of less diameter than the shell, 85 and provided with a washer for sealing said shell, substantially as set forth.

4. The herein-described shell or receptacle having open ends, removable connected sections for closing said openings, one of said 90 sections being of greater weight and of less diameter than the other whereby when said section strikes the water, it will be forced into the shell, thus opening the opposite end and allowing the contents of the shell to 95 spread upon the water, substantially as described.

Signed at New York city, in the county of New York and State of New York, this 27th day of January, A. D. 1892.

JOHN CHARLES SIMMONDS.
ALONZO PENISTON.
